UNITED STATES PATENT OFFICE.

HENRY W. POTTEIGER, OF READING, PENNSYLVANIA.

DESIGN FOR A BUCKLE.

SPECIFICATION forming part of Design No. 33,637, dated December 4, 1900.

Application filed October 24, 1900. Serial No. 34,219. Term of patent 7 years.

To all whom it may concern:

Be it known that I, HENRY W. POTTEIGER, a citizen of the United States, residing at Reading, in the county of Berks and State of Pennsylvania, have invented and produced a new and original Design for Buckles; and I do hereby declare the following to be a full, clear, and exact description of the same, reference being had to the accompanying drawings, forming a part thereof.

This invention relates to a new and original design for buckles.

In the drawings forming part of this application similar letters of reference indicate corresponding parts.

Figure 1 is a front view of my buckle. Fig. 2 is an end view of the same. Fig. 3 is a sectional view taken through line X X of Fig. 1.

The body *a* of the buckle is substantially rectangular and has an elongated slot or

opening *b* therein. The corners *c* of the body are rounded, and from the center of the lower portion of the body depends a tongue *d*. This tongue is bent on a curved line from the body and its extreme end *d'* is set on a plane 25 substantially parallel with the body *a*.

The entire buckle is formed in one piece, as illustrated in the drawings.

Having thus fully described my invention, what I claim, and desire to secure by Letters 30 Patent, is—

The design for a buckle substantially as shown and described.

In testimony whereof I affix my signature in presence of two witnesses.

HENRY W. POTTEIGER.
